Attorney

UNITED STATES PATENT OFFICE.

WILLIAM A. NIVER, OF NEW YORK, N. Y.

PAMPHLET-COVER.

1,244,886.

Specification of Letters Patent.

Patented Oct. 30, 1917.

Application filed October 11, 1915. Serial No. 55,275.

To all whom it may concern:

Be it known that I, WILLIAM A. NIVER, a citizen of the United States of America, residing in the city, county, and State of New York, have invented a certain new and useful Improvement in Pamphlet-Covers, of which the following is a true and exact description, reference being had to the accompanying drawings, which form a part 10 thereof.

The object of my present invention is the production of a book such as a magazine, pamphlet, periodical, or the like presenting a good appearance, in which the cover member attached to the body of the book in a neat and effective manner, serves not only the ordinary purpose of a book cover, but also in its original form as a wrapper for holding the book closed and in shape for 20 transportation through the mails, or otherwise, without the use of any other wrapper.

In carrying out my invention I form the cover of a single piece of material, usually flexible, with which I surround the front 25 side, back side, front edge, and back or hinge edge of the book body, leaving only the top and bottom edges of the book exposed. I permanently secure the ends of the cover piece together and the cover piece to 30 the book body at the hinge edge of the latter.

The cover thus formed when cut apart at the front edge of the book forms a cover of the usual appearance in books of the character mentioned and may have the usual 35 printed matter on its inner and outer sides. Before the cover piece is cut apart at the front edge of the book it forms an effective wrapper. By its use therefore a separate mailing wrapper is rendered unnecessary, a 40 matter of importance with a magazine for instance, having a large circulation, where the separate mailing wrappers for a single issue require many hundred pounds of paper.

45 The employment of my improved cover puts a check on the unauthorized use of the book inclosed by it, which is highly advantageous in some cases as with news companies which have frequently suffered losses 50 in the past through the acts of unscrupulous agents in wrongfully renting magazines, etc., instead of selling them. Ordinarily in such cases the customer needs to make no examination of the contents of the magazine 55 before purchasing since the title, date, char-

acter, etc., of the publication may all be shown by the printed matter borne by the outer surface of the cover.

Of the drawings,

Figure 1 is a perspective view of a magazine covered in accordance with my invention in the form issued by its publisher; 60

Fig. 2 is a perspective view of a portion of a magazine differing slightly from that shown in Fig. 1; and 65

Fig. 3 is an elevation of the front edge of the magazine shown in Fig. 2.

Referring to the drawings, 1 represents the book body. The leaves are secured together at the hinge edge of the book in any suitable manner as by staples 3, and are cut or uncut at the opposite or front edge of the book as desired. 70

The cover of the book consists of a single piece of flexible material such as paper 75 which is usually of heavier stock than the leaves forming the body of the book and of a width equal to the length of the leaves as shown in Fig. 1, or slightly longer as shown in Fig. 2. The cover piece comprises a back 80 side portion 4, a front edge portion 5, a front side portion 6, a back or hinge edge portion 7, and a narrow portion 8 which is overlapped by the adjacent end of the back side portion 4. 85

In assembling the cover, the back edge portion 7 of the cover is permanently secured to the hinge edge of the book, and the portion 8 and overlapping portion of the part 4 are also permanently secured together. 90 The securing means in each case may be paste or glue. To facilitate assembling the adhesive material may be applied to the cover piece before it is put in place.

When the cover is thus secured in place 95 the book is finished and ready for delivery. If to be mailed the address of the receiver may be printed on the cover or on a small label which may be affixed to the cover.

When it is desired to open a book thus 100 covered the cover is cut apart at the front edge of the book. To facilitate the proper severance of the cover two lines of perforations or indentations 12 are formed in the front edge portion of the book as shown in Fig. 3, and the severance of the cover is effected by tearing out the intervening strip 13. 105 In most cases the lines 12 will be so located that when the strip 13 is removed the front and back covers will be alike, and 110

will project by the front edge of the book equally, the projecting portions of the cover protecting the edge of the book.

With a book covered in the manner described the only external break in the surface of the cover in its original form is at the intersection of the hinge edge and the back side of the book, and is scarcely perceptible.

As the joint between the ends of the cover piece is at the hinge edge, by far the most rigid portion of the book, it is much more stable than it would be if located elsewhere. Moreover, when located as shown the free ends of the front and back covers when separated at the front edge of the book are perfectly smooth and flexible and the usual full page illustrations, descriptive matter, etc., may be printed on the outer surface of the book cover. The portion 8 is not wider than the usual margin at the hinge edge of the book and hence the usual matter may be printed on the inner surface of the book cover as well as on the front cover of the book.

It will be understood that the cover strips usually have printed upon them the illustrations and descriptive matter which they bear (with the exception of the address of the

subscriber or similar matter applicable to only one number of each edition) before being placed on the book body which they are to cover; and, that the covers may be applied and secured to the book bodies either manually or by suitable mechanism.

Having now described my invention, what I claim as new and desire to secure by Letters Patent, is:

A book comprising a body portion formed of leaves connected together at the back or hinge edge of the book, and a continuous cover strip which surrounds the sides, front edge and back or hinge edge of said body portion, one end of said cover strip being lapped over and secured to the other end with the end of the outer overlapping portion terminating at one corner of the book, said cover strip being permanently secured to said body portion at the hinge edge of the latter and having formed in it two lines of indentations parallel to and disposed between the front edges of the book whereby front and back book covers projecting by the front edge of the book may be formed by removing the portion of the cover strip between the lines of indentations.

WILLIAM A. NIVER.
